(57) **CLAIM**

The ornamental design for a fish tape housing as shown and described.

DESCRIPTION

- 2. Fish tape housing
- 4. Fish tape housing
- 2.1 : Perspective
- 2.2 : Perspective
- 2.3 : Front
- 2.4 : Back
- 2.5 : Left
- 2.6 : Right
- 2.7 : Top
- 2.8 : Bottom
- 4.1 : Perspective
- 4.2 : Perspective
- 4.3 : Front
- 4.4 : Back
- 4.5 : Left
- 4.6 : Right
- 4.7 : Top
- 4.8 : Bottom

Original and ornamental design for a fish tape housing. All features shown in the figures in broken lines form no part of the claimed designs. The parallel short-long-short shading lines in Figs. **4.1-4.8** denote transparent surfaces.
